Primary Examiner — Cathy A MacCormac*(74) Attorney, Agent, or Firm* — Joseph A. Yosick**(57) CLAIM**

The ornamental design for an ink cartridge, as shown and described.

DESCRIPTION

FIG. 1 is a left side elevation view of an ink cartridge showing our new design;

FIG. 2 is a front elevation view thereof; and,

FIG. 3 is a bottom plan view thereof.

The right side, rear and top views are not claimed.

Dashed broken lines showing environment or structure are for illustrative purposes only and form no part of the claimed design. Dash-dot-dash broken lines represent the border between claimed and non-claimed subject matter, are for illustrative purposes only and form no part of the claimed design.
